GEOPHYSICAL SAFETY CATCH

Lloyd R. Deputy and Lena F. Deputy,
Jennings, La.

Application November 22, 1946, Serial No. 711,564

1 Claim. (Cl. 102—21.8)

1 This invention relates to an improved construction of safety catch or anchoring member adapted for use in supporting an explosive charge at any desired position in a substantially vertically disposed tube or conduit, generally located beneath the surface of the earth.

More particularly, it is an object of the invention to provide a safety catch of the aforescribed character which is capable of being readily affixed to a cylindrical encasing sleeve of an explosive charge and provided with yieldable means for engaging the inner sides of a tubing wall for supporting the explosive charge substantially concentric with said tubing.

Still a further object of the invention is to provide a safety catch of the aforescribed character of extremely simple construction and which is capable of being economically manufactured and sold, so that the destruction of the catch, upon detonation of the charge, will not represent a material loss.

Various other objects and advantages of the invention will hereinafter become more fully apparent from the following description of the drawing, illustrating the preferred embodiment thereof, wherein:

Figure 1 is a side elevational view showing the catch in operative position applied to an explosive charge and positioned for supporting the charge in a tube or conduit;

Figure 2 is a side elevational view of the catch shown applied to an explosive charge and taken substantially at a right angle to Figure 1;

Figure 3 is a cross sectional view taken substantially along the plane as indicated by the line 3—3 of Figure 1;

Figure 4 is a fragmentary plan view of one end of the charge embracing a portion of the catch, and

Figure 5 is an end view in elevation of a retaining keeper of the charge embracing member.

Referring more specifically to the drawing, the safety catch or anchoring member in its entirety is designated generally 6 and comprises an elongated strap 7 formed of sheet metal or the like which is provided with a restricted tongue 8 at one end thereof and a transversely disposed slot 9, adjacent its opposite end. The strap or encompassing member 7 is adapted to extend around a portion of the enclosing sleeve 10 which forms a container for an explosive charge 11 and the tongue 8 is passed outwardly through the slot 9 and turned back upon itself to overlie the end of the strap 7 from which said tongue 8 projects, as seen in Figure 1. The tongue 8, before being

turned back upon itself, as previously described, is drawn through the slot 9 sufficiently so that the strap 7 will engage relatively tight around the sleeve 10. The portion of the end of the strap 7, which is engaged by the turned back end of the tongue 8, carries a keeper 12 which is likewise formed of a relatively narrow strip of sheet metal. The intermediate portion of the keeper 12, as seen in Figures 1 and 2, is disposed over a portion of the outer side of the strap 7 and over a part of the turned back end of the tongue 8 and transversely of said part. The ends 13 of the keeper 12 are turned inwardly and back upon themselves and are disposed beneath a portion of the strap 7 and are retained, thus positioned, by being clamped between said portion of the strap 7 and the sleeve 10. The intermediate portion of the keeper 12 engages the tongue 8 sufficiently close to prevent the turned back portion of the tongue sliding relatively thereto, so as to retain the strap or belt 7 in an applied position around the encasing sleeve 10. To prevent sliding movement of the applied strap 7 relatively to the sleeve 10, said strap is provided at circumferentially spaced intervals with pairs of prongs 14 which are struck inwardly from the body of the strap 7 and each of which is substantially V-shaped. The individual prongs 14 of each pair of prongs, are transversely spaced and the tapered pointed ends thereof, before being struck inwardly, extend toward one another. The inwardly struck prongs 14 are embedded in the sleeve 10 and may extend slightly into the charge 11 for securely anchoring the strap 7 to prevent it from sliding relatively to said sleeve 10.

As best seen in Figure 3, the strap or encircling belt 7 is provided with substantially diametrically opposed outwardly extending arcuate portions 15. The catch 6 also includes a strand of relatively heavy gauge, resilient wire, designated generally 16 having an arcuate intermediate portion 17 which extends substantially half-way around the sleeve 10 and beneath the strap 7 and the ends of which terminate in upwardly extending leg portions 18, which are disposed substantially at right angles to the plane of the arcuate portion 17 and which extends through the strap portions 15 to be clamped thereby against portions of the sleeve 10. The leg portions 18, directly above the upper edge of the strap 7, are provided with outwardly extending portions 19 which engage over the upper edges of the portions 15 to prevent downward sliding movement of the leg portions 18 relatively to said portions 15. The terminals

or legs 20 of the wire strand 16 project upwardly in diverging relationship to one another from the outwardly extending portions 19 and terminate at their free ends in outturned terminals 21 which are adapted to frictionally and yieldably engage the inner surface of the wall of a tube or conduit 22 in which the explosive charge 10, 11 and the safety catch 6 is disposed. As clearly illustrated in Figure 1, it will be readily apparent that the catch 6 will normally support the explosive charge within the tube 22 and substantially concentric therewith.

It will be readily apparent that the explosive charge with the safety catch 6 applied thereto may be forced downwardly in the tubing 22 by any suitable and conventional means, not shown, and the resiliency of the legs 20 will permit the terminals 21 thereof to slide relatively to the tubing wall while the charge is thus being forced downwardly in the tubing. However, the legs 20 are of sufficient strength to resiliently retain the terminals 21 in frictional engagement with the wall of the tubing 22 so as to support the charge in any position to which it is moved and when a force is no longer being exerted thereon to force the charge downwardly.

Obviously, the size of the safety catch 6, including the length of the strap 7 and the length, gauge and resiliency of the strand 16 may be varied to accommodate charges of different sizes and to provide legs 20 of sufficient strength for supporting charges of different weights. Various other modifications and changes are likewise contemplated and may obviously be resorted to, without departing from the spirit and scope of the invention as hereinafter defined by the appended claim.

We claim:

In combination with an explosive charge en-

closing sleeve, a spring support mounted on the sleeve and adapted to support it in a vertical conduit, said spring support including a resilient strand and a sleeve encircling metal strap securing the strand to the sleeve, said strap having fastening means adjustably connecting the ends thereof and securing the strap around the sleeve, inwardly extending prongs struck from the strap and embedded in the sleeve, said strap having oppositely disposed outwardly offset portions, said strand having an arcuate intermediate portion engaging partially around the sleeve below the strap, said arcuate intermediate portion terminating in upwardly extending leg portions disposed between the sleeve and the outwardly offset portions of the strap, said strand having corresponding upwardly diverging end portions projecting from the upper ends of said upwardly extending leg portions each having an outturned conduit wall engaging terminal, said upwardly diverging end portions being biased outwardly by the resiliency of the strand for urging the outturned terminals into frictional engagement with the wall of the conduit to support the charge enclosing sleeve in the conduit.
